(57) **CLAIM**

The ornamental design for an inflatable wedge for diving onto a water slide, as shown and described.

DESCRIPTION

FIG. 1 is a front and right side perspective view of an inflatable wedge for diving onto a water slide showing my new design;

FIG. 2 is a rear and left view thereof;

FIG. 3 is a right-side elevational view thereof;

FIG. 4 is a left-side elevational view thereof;

FIG. 5 is a top plan view thereof;

FIG. 6 is a bottom plan view thereof;

FIG. 7 is a front elevational view thereof; and,

FIG. 8 is a rear elevational view thereof.
